(57) **CLAIM**

The ornamental design for a light for hand tool, as shown and described.

DESCRIPTION

FIG. 1 is a perspective view of a light for hand tool showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the light mounted on a hand tool.

The broken lines showing of the hand tool in FIG. 8 illustrate the environment of the claimed design and form no part thereof.
